UNITED STATES PATENT OFFICE

MAX STEINMÜLLER, OF CHEMNITZ, GERMANY

CIRCULAR KNITTING MACHINE

Application filed January 31, 1931, Serial No. 512,670, and in Germany December 18, 1929.

The present invention relates to circular knitting machines, being an improvement over the type shown in my co-pending application Serial No. 135,231, filed March 2, 1926, now Patent No. 1,831,773.

Stockings manufactured on the circular knitting machine are now contracted in the calf like stockings produced on Cotton's machine, but are widened by means of additional needles, so that the known fashioning loops characteristic of Cotton stockings do not appear in circular knitted stockings. According to the invention, in order to give stockings manufactured on the circular knitting machine a similar appearance to Cotton stockings, the loops are thickened or piled on both sides of the seam to form marks similar to those made by the fashioning loops of Cotton stockings. This is effected by means of rotating push levers which at the given moment bring the necessary needles into the range of special locking elements by which they are raised, so that instead of a loop being formed the thread is merely wound around the needle or laid in the needle head.

An advancing device is also provided in order to ensure that the needles to be displaced for the purpose indicated are always at the same distance from the edge of the article, so that the loops form a row which is parallel to the seam, as in the case of stockings made on Cotton's frame.

Reference will now be made to the accompanying drawings which illustrate an embodiment of the invention by way of example and in which:

Figures 1 and 2 each illustrate a stocking provided with imitation fashioning loops according to the invention. In Figure 1 they are arranged singly, whereas in Figure 2 they lie adjacent each other in pairs.

Figure 3 is a plan view of one half of the advancing device, and

Figure 4 is a plan of the other half thereof.

Figure 5 is a plan of the entire advancing device on a smaller scale.

Figure 6 is a front elevation of one half of the advancing device, and

Figure 7 is an elevation of the other half.

Figure 8 is a plan view of Figure 6.

Figure 9 is a plan view of Figure 7.

Figure 10 is a side view of the advancing device looking in the direction of the arrow *a* of Figure 5.

Figure 11 illustrates part of the device looking in the direction of the arrow *b* of Figure 5.

Figure 12 illustrates various individual elements of the device in side elevation or section looking in the direction of the arrow *b* of Figure 5 but from the middle of the needle cylinder.

Figure 13 is an illustration of the lock.

Figures 14 and 15 show different positions of the needle in two axial sections through the needle cylinder and the adjacent machine parts.

Figure 16 is a side elevation of one of the rotary push levers.

Figure 17 is a side view of the entire machine.

Referring to Figures 1 and 2, the rows of loops are indicated by vertical lines and the imitation fashioning loops by the crosses 1. The distance of the latter from the edge of the stocking is fourteen loops, but this may be increased or decreased as desired. In Figure 1 there is only one fashioning loop in each row of loops, while in Figure 2 two loops are disposed side by side on two adjacent rows of loops.

Although the invention is here described as applied to a circular knitting machine having a rotating needle cylinder, it may also be applied to machines having a rotating lock cover.

The machine operates in known manner in a pendulum movement while the article is being made.

The needles 2 intended for forming the fashioning loops are provided with a special foot 3 according to Figure 13. The lock parts 5, 6, 7 and 8 are provided on the lock cover and the needles 2 are mounted on the needle cylinder so as to be displaceable by means of rotary push levers 10 in such a manner that their feet 3 can be selectively brought into the range of the lock elements 5 and 6 which are disposed at a certain distance from the needle cylinder 11. When

this takes place in the manner hereinafter described the needle is raised to the position indicated in dotted lines in Figure 14, so that the known working foot 4 runs over the middle part 9 of the lock (Figure 13) and a loop is prevented from forming on this needle. Thus a loop is only set on this raised needle, and this may be repeated if desired. The needles are returned to the normal position 10 by the lock parts 7 and 8.

The rotatable levers 10 shown in Figures 14-16 are disposed in suitable grooves, 15 of the needle cylinder 11 by means of their segmental projections *e*. The upper arm *d* of 15 the lever applies itself against the lower part of the needle 2 on the side nearest the cylinder, while the lower arm possesses a projection *f* against which the buffers 18 or 29 press when the lever is to be rocked and the 20 needle 2 brought into the range of the lock element 5. The cavity *g* of the lever serves to receive the known cylinder springs by which the lever 10 is held to the needle cylinder.

25 The buffers 18 and 29 are mounted in slides 16 and 17 respectively so as to be displaceable radially to the axis of the needle cylinder 11. The slides 16 and 17 are supported on the cogged segments 22 and 23 and are 30 adapted to be displaced along the latter. The intermittent advancement is effected by means of the pawls 19 and 20 in the manner described hereinafter. The lower toothed segment 23 is rigidly connected with the bearings 24, 25 and 26, which also serve to guide the two segments 22 which are displaceably mounted on the segment 23. The segments 22 are secured against removal by the cover 42. The bearings 24, 25, 26 are parts of the 35 frame 12 which is secured by the screws 13 to the needle cylinder 11.

The automatic displacement of the needles 2 is effected from the advancing drums 27 and 28 (Figures 6-9) upon which cam elements are screwed in suitable manner through which the adjustment levers are actuated. The process of advancing the needles is divided into three stops; the intermittent displacement of the slides 16 and 45 17 along the segments 22 and 23, the radial displacement of the buffers 18 and 29 by a bracket 30 carried by the machine frame, and the return of the slides 16 and 17 to the initial position.

50 At the commencement of the process the slide 17 is in the position shown in Figure 5 (top), when the stop 21 or 31 lies adjacent the bearing 26. Now if the slide is to be displaced the cam 33 of the drum 28 acts on the nose of the lever 32 as shown in Figure 6. At the end of the other arm of this lever a pin 35 is situated, which is connected with an arm of the lever 36, which rotates about the axis 37. The other end of this lever forms the stop 38. 55 The position of the lever 36 indicated in Figure

60 ure 6 is its contact position. As the cylinder 11 rotates, the end of the one armed lever 39 mounted on the bearings 24 and 26 strikes the contact point 38, whereby the lever turns through a small angle about its bearing screw 41. This rotation serves to advance the slides 16 and 17 along the segments 22 and 23. The pawls 19 (Figure 10) engage in the upper segment 22 and the pawls 20 or 79 in the lower segment 23, which are mounted on the slides 16 and 17, so that when the segments 22 move to and fro said slides are displaced. In the range of the lever 39 the segment 22 possesses a pin 40 which is moved by said lever 39. To permit this, the cover 42 has a slot 43. The slide is always displaced through only one cog division. The segment 22 is returned after every advancement by the tension spring 45 which pulls on the pin 40 and is secured at its other end to the hook 44. In the movement in one direction the segment 22 carries along the slide 16 or 17 by means of the pawl 19, whereupon the slide secures itself to the rigid segment 23 by means of the pawl 20, and the pawl 19 slides ineffective over the teeth of the segment 22 when the latter returns. The pawls 19 and 20 are held in contact with the segments 22 or 23 by the springs 46 and 47 respectively. Each time the lever 39 meets the stop 38 the slides are caused to advance 55 through one cog division.

Figure 15 shows the needle 2 in the normal position. The lower foot 3 goes past the lock element 5. Figure 14 shows the lower foot 3 of this needle moved into the range of the lock element 5. In this position of the needle the thread is laid but a stitch is not formed.

The needle foot 3 is advanced into the position shown in Figure 14 through the intermediary of the push lever 10 by the buffers 18 and 29 (Figures 3, 14 and 15). These buffers are displaced radially to the cylinder axis when their outer surfaces run on the bevel 48 of the bracket 30 as the cylinder 11 revolves. The other end 49 of the buffer is narrowed down so that it can act only on one lever 10. This end of the buffer presses back the part *f* of the lever 10 as it is displaced, whereby the upper arm *d* of the lever applies itself against the lower part of the needle 2 and presses it forward to such an extent that the needle foot 3 comes into the range of the lock element 5.

The bracket 30 is vertically displaceable. For this purpose it is secured by means of the clamps 50 and 51 to the bolts 52 and 53, which are mounted on the bearings 54 and 55 (Figures 6 and 7). This displacement of the bracket 30 is effected from the drum 25 by a cam element pressing back the nose of the lever 56 which turns about the screw 57. The other arm of this lever transmits the movement through the rod 59 to the lever 60 which is fulcrumed at 61. The other arm of the lever 60 possesses a slot in which the pin 65 of the 125 65

clamp 64 engages. The clamp 64 carries the shaft 66 which by means of the angle cramps 62 and 63 forms the connection with the two vertical bolts 52 and 53. If the lever 56 is moved away from the drum 28, the bracket 30 is displaced.

The contact points of the two buffers 18 and 29 are not similarly situated. In buffer 18 (Figure 14) the stop is situated higher than in the buffer 29 (Figure 15). Accordingly a two stepped cam element 58 on the drum 28 is used to displace the lever 56. When the nose of the lever 56 lies adjacent the drum 28 the bracket 30 stands above the stops of the buffers 16 and 29 (Figure 15). When the nose of the lever 56 runs on the lower step of the cam 58 the bracket 30 is lowered so that the contact point of the buffer 18 runs on the bevel 48 of the bracket. This position is shown in Figure 14. If the nose of the lever 56 runs onto the upper step of the cam 58 the bracket descends to the level of the contact point of the buffer 29 (shown dotted in Figure 14).

During the production of the calf portions of the stocking one of the needles 2 is always raised by means of the above described arrangement when an imitation fashioning loop is to be formed. By the displacement of the slides 16 and 17 on the segments 22 and 23 it is ensured that the fashioning loops all have the same distance from the edge of the calf portion. The buffers 18 and 29 always displace the needles only a certain number of rows of loops so that the fashioning loops are all formed at the desired distance from one another.

When the calf has been completed in this manner and no further fashioning loops are required the slides 16 and 17 must be brought back to the original position. For this purpose the pawls 20 and 79 are drawn back, and to this end they are provided on their lower side with a projection 68 and on their upper side with a pin 67. The latter merely has the purpose of taking the pawl 19 with it during the uncoupling movement, while the projection 68 co-operates with a bracket 69. The latter is mounted on the machine frame and is adapted to oscillate about the axis 70 and is coupled at the other end by the screws 83 to a bracket 78. This is pressed by the spring 71 into such a position that the projection 68 cannot come into contact with the bracket 69 during the rotation of the needle cylinder. The displacement of the bracket is effected from the drum 27. When the nose of the lever 73 runs onto the cam 72 of this drum the lever 73 is displaced and the movement is transmitted from its other arm through the connecting rod 74 to the lever 75. This carries a set screw 77 which runs on a bevelled portion of the bracket 78 and thereby presses back the latter against the pressure of the spring 71.

Thus the bracket 69 is displaced in such a manner that the projection 68 of the pawls 20 and 79 runs onto the outer surface of the bracket 69, so that the pawls 19, 20 and 79 are lifted off the toothed segments 22 and 23. As soon as this takes place the springs 81 and 82 draw the slides 16 and 17 back to their initial position, when the stops 21 or 31 apply themselves against the bearings 24 or 26.

I claim:

1. In a circular knitting machine, the combination of a needle cylinder with a plurality of needles disposed on the said cylinder, a plurality of heels forming part of some of the needles, means for pressing the heels of the needles away from the said cylinder and within range of cams adapted to move the needles thus adjusted, arched carriers secured to the said needle cylinder, carriages displaceably disposed on the said carriers, drivers carried by the said carriages and adapted to actuate the said means for adjusting the needles, ratchet teeth on the said carriers, another toothed segment displaceably arranged on the said carriers, two pawls rotatably disposed on each of the said carriages, one of the said pawls being in engagement with the teeth of the carrier and the other one with the said toothed segment, and means for reciprocating the said toothed segment.

2. In a circular knitting machine, the combination of a needle cylinder with a plurality of needles disposed on the said cylinder, a plurality of heels forming part of some of the needles, means for pressing the heels of the needles away from the said cylinder and within range of cams adapted to move the needles thus adjusted, arched carriers secured to the said needle cylinder, carriages displaceably disposed on the said carriers, drivers carried by the said carriages and adapted to actuate the said means for adjusting the needles, ratchet teeth on the said carriers, another toothed segment displaceably arranged on the said carriers, two pawls rotatably disposed on each of the said carriages, one of the said pawls being in engagement with the teeth of the carrier and the other one with the said toothed segment, means for reciprocating the said toothed segment, projecting portions on the said pawls, a guide bar positioned within range of the said projecting portions on the machine frame and adapted to lift by its motion the said pawls out of the said ratchet teeth and the said toothed segment, and a spring adapted to return the said carriages to their initial positions.

In testimony whereof, I have affixed my signature.

MAX STEINMÜLLER.
